UNITED STATES PATENT OFFICE.

GEORGE H. SHELLABERGER, OF BARTOW, FLORIDA.

SAW-TOOTH WRENCH.

SPECIFICATION forming part of Letters Patent No. 705,454, dated July 22, 1902.

Application filed April 7, 1902. Serial No. 101,789. (No model.)

To all whom it may concern:

Be it known that I, GEORGE H. SHELLABERGER, a citizen of the United States, residing at Bartow, in the county of Polk and State of Florida, have invented certain new and useful Improvements in Saw-Tooth Wrenches, of which the following is a specification.

My invention relates to wrenches, and more particularly to that class of wrenches which are employed in withdrawing removable saw-teeth from the cutting edges of circular and other saws. In many forms of power-operated saws, and more especially those of the circular type, the cutting members or teeth thereof are made separable and removable for purposes of sharpening the same when they become dull and replacing old and worn-out teeth by new ones. The act of removing and reinserting these teeth in their seats in the margin of the saw blade or disk has heretofore been accompanied by considerable danger and risk to the operator, owing to the fact that the tools hitherto employed in applying and removing these saw-teeth have, so far as I am aware, been unprovided with means for securing the tool to the tooth beyond all possible danger of a slip of the tool off the tooth when the power is applied by the hand of the operator, and hence great care has had to be exercised by the operator in manipulating the tool lest his hand should accidentally be thrust in contact with the sharp teeth of the saw, with the resulting cutting and lacerating of that member that inevitably follows such a mismovement.

The primary object of my invention is to produce a wrench specially adapted for the application and removal of saw-teeth possessing such a construction and mode of manipulation as to secure a hold upon the tooth which is proof against accidental slip or displacement, and thus entirely obviate the dangers above referred to.

Another object of the invention is to produce a wrench of the character specified which shall be capable of use in connection with teeth of varying forms and sizes. Other minor objects of the invention will appear later in the following description.

To these ends my invention consists in a saw-tooth wrench possessing the peculiar

characteristics of structure and mode of manipulation substantially as hereinafter described, and more particularly pointed out in 55 the claims.

In the accompanying drawings, Figure 1 is a side elevation of the head and arm or shank portions of my improved wrench, the outer or handle end of the latter being broken off. 60 Fig. 2 is a bottom edge view of the wrench as shown in Fig. 1. Fig. 3 is a side elevational view showing the wrench partially applied to a saw-tooth for the removal of the same. Fig. 4 is a view similar to Fig. 3, but 65 showing the wrench in full operative position upon a slightly - different construction of tooth. Fig. 5 is a similar view illustrating a modified form of the wrench partially applied to a tooth of the form shown in Fig. 4. 70 Fig. 6 is a side elevational view of a portion of the disk of a circular saw, illustrating the manner in which the removable teeth are seated and secured therein; and Fig. 7 is a detail transverse sectional view on the line 75 77 of Fig. 5, illustrating the manner in which the tooth is seated in the saw-disk.

In the drawings, 8 designates the disk of a circular saw mounted upon a driving shaft or arbor 9. The peripheral margin of this 80 disk is provided at regular intervals with a series of shallow curved notches 10, constituting seats for the removable saw-teeth 11 and their shanks 12. These seats are formed for the greater part upon arcs of circles; but 85 the upwardly - extending end of each seat which is opposite to the saw-tooth proper and which engages the rear end or heel of the shank 12 is given an inward turn off from the arc of the circle, so as to constitute in association with said tooth-shank a stop or abutment having a wedge-like form and action. As shown in Fig. 7, the cut-out concave margin of the seat is beveled on both sides, thereby providing throughout the entire extent of 90 the seat a longitudinally-extending V-shaped ridge or tenon 8^a, which is adapted to snugly fit and coöperate with a corresponding peripheral groove 12^a, formed in the coöperating convex margins of the removable teeth and 95 their shanks.

The teeth and their shanks formed as above described and fitting in and coöperating with the margin of the saw-disk in the manner set

forth and shown are old and well known in the art of power-saws. For the purposes of inserting and removing the teeth 11 and their holders or shanks 12 the latter are commonly 5 provided with one or more openings formed transversely through the shank-section of the tooth. In Figs. 3 and 6 I have shown a tooth the shank whereof is provided with a pair of transverse holes 13 and 14, located, respectively, adjacent the forward and rear ends of the shank. In Figs. 4, 5, and 6 I have shown a similar but slightly smaller form of tooth-shank provided with but the single hole 13, formed therethrough near its forward end. 15 My invention is equally well adapted to co-operate with either form of tooth-shank, as well as with teeth wherein the holes 13 and 14 are located at varying distances apart.

Referring now to the construction of my 20 improved wrench, which has been especially designed for co-operation with removable saw-teeth of the character hereinabove referred to, 15 designates the head of the wrench, which is constituted by a flat metal plate of considerable thickness, as shown in Fig. 2, and having an irregular outline, preferably 25 of the general form illustrated in Fig. 1. For purposes of convenient description I refer to the several parts or sections of the 30 wrench-head 15 as consisting of a nose 15^a, a back 15^b, and a heel 15^c. The nose 15^a is transversely apertured by an internally-threaded hole to receive and seat a pin 16, that portion of the pin engaging the threaded 35 aperture referred to being externally threaded and the pin having fast on the outer end thereof a head in the form of a nut 16^a, whereby it may readily be screwed into place. The back portion 15^b of the wrench-head is 40 provided with an integral lateral boss 17, the back and boss being transversely apertured to receive a bolt 18, passed therethrough, which bolt is provided on one end with a square head 19 and a removable washer 20 45 and at its other end is externally threaded to receive a binding-nut 21.

To the outer face of the boss 17 is applied the lower end of the wrench-shank 22, which latter is herein shown as comprising simply 50 a straight flat metal bar of uniform width and thickness throughout. The extreme lower end of the bar 22 is provided with a notch of a suitable size to engage the pin 16 in the manner clearly shown in Fig. 4. It will be noticed that this notch has a mouth 23, formed 55 of a uniform width just sufficient to embrace the bolt 16, while in rear thereof the notch is given a circular formation, as shown at 24, of a diameter somewhat exceeding the width of 60 the mouth 23. The purpose of this peculiar formation of the notch will appear later in the description of the operation.

The lower end of the shank-bar 22, just 65 back of the notch 24, is provided with a longitudinal slot 25 of a width sufficient to permit the passage of the bolt 18 therethrough with facility for the bar to slide freely there-

over to the extent permitted by the length of the slot. In practice this slot is made long enough to facilitate the ready application and 70 withdrawal of the notch 24 to and from the forward bolt 16 in the act of applying the wrench to and removing it from a tooth. The rear or heel portion 15^c of the wrench-head is provided with a slot 26, extending longitudinally thereof, which slot on that side of the head which is adjacent the bar 22 is countersunk on the sides thereof to about one-half the depth thereof, as shown at 27. Through 75 this slot is passed a pin 28 similar to the pin 16, the pin 28 being confined in the slot with freedom for adjustment to any desired position longitudinally thereof by means of a pair of nuts 29 and 30, the former of which engages the outer end of the pin and the adjacent outer face of the wrench-head, while the inner nut 30 has a sliding fit within the countersunk side of the slot 26. By applying an ordinary wrench to the outer nut 29 the same 80 may be loosened to set the pin 28 at any desired position, after which by turning up the nut 29 the pin is rendered rigid relatively to the wrench-head.

The operation of the hereinabove-described wrench and its manner of application to a 95 saw-tooth to be inserted or removed thereby is substantially as follows: Referring to Figs. 1, 2, and 3, the head of the wrench is applied to one side of the tooth, and the pin 28 is adjusted and secured in such a position that the 100 two pins 16 and 28 will respectively register with and enter the openings 13 and 14 in the shank member of the tooth, the arm 22 being retracted to enable the adjacent faces of the wrench-head and of the tooth-shank to lie 105 snugly in contact. By reason of the presence of the thickened portion or boss 17 of the wrench-head, which is of substantially the thickness of the saw-tooth and which lies in the same plane as the latter, the lower end of 110 the operating-arm 22 is caused to overlie the opposite side of the tooth, and upon then pushing downwardly and forwardly the said arm the notch 24 in the forward end thereof may be 115 carried over and caused to engage the pin 16 in the manner clearly indicated in Fig. 4, the lower end of the arm thus lying in substantial contact with the inner side of the tooth, opposite to that side which is contacted by the wrench-head 15. In this manner the 120 wrench-head and arm are afforded a secure hold upon the shank of the tooth at two separated points therein and on both sides thereof. It will be obvious that by then depressing the outer end or handle of the wrench-arm 22 the tooth and its shank will be rocked in their seat in a direction to first expel the tooth member 11 and subsequently withdraw 125 also the shank member 12. In this operation it will be observed that the wrench completely 130 straddles the saw-tooth, engaging the latter on both sides thereof and thus affording a central purchase in the plane of the tooth itself, which effectually prevents any tendency

on the part of the wrench to fly off to one side or the other irrespective of the particular character of the hold of the wrench upon the tooth. The principal fault in devices heretofore employed for this purpose has been that they engaged the tooth on one side only and to one side of the plane of the tooth, thereby creating a liability of the tool to slip off the tooth when pressure was applied, often to the serious injury of the operator. When the tooth has been properly sharpened or replaced by a new tooth, the parts may be replaced in their seat by the converse of these operations, the heel or tail of the shank being first introduced, after which by elevating the outer handle of the tool the tooth may be forced by the lever action of the latter into secure locking engagement with its seat. This done, the operator first withdraws the arm 22 to the extent indicated in Figs. 1 and 3 and then removes the wrench-head laterally from the saw-disk, this operation withdrawing the pins 16 and 28 from the tooth-shank, thus entirely disengaging the tool.

Where the tool is applied to a tooth such as is shown in Fig. 4, having but a single hole in the forward end of the shank, the pin 28 is adjusted to occupy the inner end of its containing-slot, and in the operation of extracting the tooth the pin 28 bears against the inner concave edge of the shank, constituting therewith a fixed thrust-point on which the force applied downwardly to the end of the handle may be made effective to rock and slide the tooth out of locking engagement with its seat. In the converse operation of replacing the tooth in its seat the nose 17^a of the boss abuts the upper end of the inner curved margin of the tooth-shank in the manner shown, constituting therewith a fixed thrust-point on which the force applied upwardly to the end of the handle may be made effective to rock the tooth inwardly into locked engagement with its seat. It will be evident that the wrench is capable of application in this manner to a tooth such as is shown in Fig. 4 if desired; but where the tooth-shank is provided with a hole at each end thereof I prefer to engage both pins there-with for the purpose of obtaining a more rigid and secure hold upon the tooth.

Fig. 5 illustrates a slightly-modified form of wrench-head adapted for coöperation with either the tooth shown in Fig. 3 or that shown in Fig. 4, but more particularly designed for application to the latter form. In this case the boss 17^b on the side of the wrench-head is provided on its under side with a V-shaped point 17^c, which formation can be easily secured by making the boss substantially triangular in shape, as shown. In the application of this form of wrench to the tooth the point 17^c bites the inner concave edge of the tooth-shank, constituting therewith a thrust-point to render effective the force applied downwardly to the outer end of the handle, while the forward point or nose 17^d of the tri-

angular boss constitutes, with the inner opposite edge of the tooth, a thrust-point for the insertion and locking of the tooth to its seat, 70 all in the manner above described in connection with Fig. 4.

In the several operations described it will be observed that the circular formation of the notch 24 in the forward end of the arm 22 in association with the mouth 23 of just sufficient width to pass over the pin 16 affords a very secure seat for the pin when either a downward or upward pressure is applied to the handle of the wrench, the pin being capable of removal from the notch only by a direct outward pull upon the handle. This practical interlocking of the pin with the nose of the operating-arm of the tool during those movements of the latter wherein the tooth is 85 being removed or inserted contributes largely to the safety of the implement for the purpose described.

From the foregoing it will be seen that my invention provides a tool easy of application 90 to varying sizes of removable saw-teeth and affording an effective hold thereon for the purposes of tightening and loosening the same in its seat, at the same time, by reason of its peculiar construction and manner of attachment, entirely eliminating all possibility of an accidental slip thereon, with the injurious consequences often resulting from such insecure hold of the tool on the object to which it is applied. The safety feature of my invention is still further enhanced by the fact that the tool is provided with a comparatively long shank and handle extending at a considerable angle from the underlying line of the saw-teeth, and hence permitting considerable freedom of movement of the hand of the operator without danger of contact with the saw-teeth.

I am aware that numerous changes and modifications might be made in the detail features of my invention without altering its character and substance. I do not, therefore, limit myself to the precise forms and relative arrangement of the several coöperating elements herein shown and described, except to 115 the extent that they may be made the subject of specific claims.

I claim—

1. A saw-tooth wrench, comprising in combination a wrench-head provided with a plurality of tooth-engaging devices thereon, and an operating-arm connected with said head and removably engaging one of said tooth-engaging devices on the opposite side of the tooth, substantially as described.

2. A saw-tooth wrench, comprising in combination a wrench-head provided with a pair of tooth-engaging devices at longitudinally-separated points thereon, and an operating-arm connected with said head and removably engaging one of said tooth-engaging devices on the opposite side of the tooth, substantially as described.

3. A saw-tooth wrench, comprising in com-

bination a wrench-head provided with a pair of tooth-engaging devices at longitudinally-separated points thereon, and an operating-arm slidably secured to said head and removably engaging one of said tooth-engaging devices on the opposite side of the tooth, substantially as described.

4. A saw-tooth wrench, comprising in combination a wrench-head provided with a pair of tooth-engaging devices at longitudinally-separated points thereon, one of which is adjustable, and an operating-arm slidably secured to said head and removably engaging one of said tooth-engaging devices on the opposite side of the tooth, substantially as described.

5. A saw-tooth wrench, comprising in combination a wrench-head provided with a pair of laterally-extending tooth-engaging pins at longitudinally-separated points thereon, the foremost of which is fixed and the rearmost of which is adjustable, and an operating-arm slidably secured to said head and adapted to removably engage the foremost of said pins on the opposite side of the tooth, substantially as described.

6. A saw-tooth wrench, comprising in combination a wrench-head provided with a pair of laterally-extending tooth-engaging pins at longitudinally-separated points thereon, and an operating-arm slidably secured to said head and provided with a notch adapted to

removably engage one of said tooth-engaging pins on the opposite side of the tooth, substantially as described.

7. A saw-tooth wrench, comprising in combination a wrench-head provided with a pair of laterally-extending tooth-engaging pins at longitudinally-separated points thereon, and an operating-arm slidably secured to said head and provided in its forward end with a notch adapted to removably engage the foremost of said tooth-engaging pins on the opposite side of the tooth, substantially as described.

8. A saw-tooth wrench, comprising in combination a wrench-head provided with a pair of laterally-extending tooth-engaging pins at longitudinally-separated points thereon, the foremost of which is fixed and the rearmost of which is adjustable, and further provided with a third laterally-extending pin located above and between said tooth-engaging pins, and a slotted operating-arm mounted on said last-named pin and provided in its forward end with a notch adapted to removably engage the foremost of said tooth-engaging pins on the opposite side of the tooth, substantially as described.

GEORGE H. SHELLABERGER.
